FIG. 1

FIG. 2

Louise Pfuhl INVENTOR.

UNITED STATES PATENT OFFICE

115,350

DESIGN FOR A PLATE OR SIMILAR ARTICLE

Louise Pfuhl, Rochelle Park, N. J.

Application July 14, 1938, Serial No. 78,478

Term of patent 14 years

To all whom it may concern:

Be it known that I, Louise Pfuhl, a citizen of the United States, residing in Rochelle Park, in the county of Bergen, State of New Jersey, having invented a new, original, and ornamental Design for a Plate or Similar Article, of which the following is a specification, reference being had to the accompanying drawing, forming a part thereof.

Figure 1 is a top plan view of a plate or similar article, showing my new design; and

The design is characterized by the border ornamentation of the plate which consists of two separate and different flower groups superimposed by a scroll, and the alternate arrangement of flowers from each of the groups at five separated areas around the border of the plate, the said scroll superimposed groups forming a predominating head for the assembly, all as shown.

I claim:

The ornamental design for a plate or similar article, as shown and described.

LOUISE PFUHL.
